UNITED STATES PATENT OFFICE.

FERDINAND KULHAWY, OF GUTTENBERG, NEW JERSEY.

DESIGN FOR A RADIO APPARATUS MULTIPLE DIAL.

Application filed March 18, 1926. Serial No. 16,965. Term of patent 3½ years.

To all whom it may concern:

Be it known that I, FERDINAND KULHAWY, citizen of the United States, residing at Guttenberg, county of Hudson, and State of New Jersey, have invented a new, original, and ornamental Design for a Radio Apparatus Multiple Dial, of which the following is a specification, reference being had to the accompanying drawings forming a part thereof.

Fig. 1 is a front elevation of the embodiment of my design;

Fig. 2 is a side view thereof.

I claim:

The ornamental design for a radio apparatus multiple dial substantially as shown.

FERDINAND KULHAWY.
